MOLL, OF SAME PLACE.

CURTAIN-FIXTURE.

SPECIFICATION forming part of Letters Patent No. 660,405, dated October 23, 1900.

Application filed April 23, 1900. Serial No. 13,942. (No model.)

To all whom it may concern:

Be it known that we, CHARLEY B. TITUS and MONTFORD C. MCMAINS, residing at Little River, in the county of Rice and State of Kansas, have made certain new and useful Improvements in Curtain-Fixtures, of which the following is a specification.

This invention is an improvement in curtain-fixtures, and particularly in fixtures which may be attached to the window-sash, so that they will raise and lower with the sash; and the invention consists in certain novel constructions and combinations of parts, as will be hereinafter described and claimed.

15 In the drawings, Figure 1 is a perspective view of our invention as in use. Fig. 2 is a rear perspective view of the bracket. Fig. 3 illustrates the bracket in detail, including the means for locking the sliding section in any 20 desired adjustment, and Fig. 4 illustrates the curtain-bearing portion in detail.

The bracket A is composed of a main section A' and a sliding section B. The main section A' is formed with a strut-brace or plate 25 C, and with a top plate D, such plates C and D having at their inner ends perforated lugs C' and D' to facilitate securing the same in place. The outer end of the top plate D connects with the upper end of the strut-brace 30 C and is notched at d in its opposite edges at its juncture with the upper end of the strut-brace C, thus forming ways for the guide and retaining flanges on the sliding section and exposing the upper end of the strut-brace at 35 its edges, so that the said flanges may be indented or compressed above the strut-brace to lock the sliding section in any desired adjustment, as will be more fully described herein-after. The sliding section is adjustable along

40 the strut-brace of the bracket A, so that it may be set in or out and adapt the bracket to windows of different depths, such sliding section B being provided at its upper outer end with means by which to support the curtain-bearing portion. (Shown in Fig. 4 and presently described.)

In the construction shown, and which is preferred, we form the sliding section B with edge flanges B', which are inturned to overlap the 45 edges of the sliding section and which oper-

ate in the notches of the top plate D, as shown. These flanges extend to the upper end of the sliding section and reinforce at such points the edges of such section to give the desired rigidity to the arms formed at such edges of 55 the section B to retain the curtain-bearing portion, as presently described. In the upper end of the sliding section B we form slits E, spaced apart and producing a central tongue E', which is deflected relatively to the edge 60 portions or bars E², so that the curtain-bearing portion may be inserted in the seat formed at the upper end of the sliding section B, as will be understood from the drawings.

In operation the bracket is secured to the 65 window-sash or otherwise, as desired, and the section B is adjusted along the strut-brace to bring the outer end of the section B to the desired position. When this adjustment is effected, the flanges B' may be indented or compressed 70 above the upper outer end of the strut-brace C to prevent the section B from sliding down on the brace-plate, thus locking the section B in the desired adjustment. The curtain-bearing portion, as shown in Fig. 4, 75 is composed of the sections G and H, having at their outer ends lugs to support the curtain-roller, and one of said plates having at its inner end extensions, inturned at H', to overlap the other section, so that the support 80 can be readily extended longitudinally to any desired degree.

The invention is simple and can be conveniently adjusted or secured to the window-sash or other support and set in or out to support 85 the curtain in the desired arrangement.

Having thus described our invention, what we claim, and desire to secure by Letters Patent, is—

1. The bracket having an inclined or strut 90 brace and a top plate bracing the upper end of the strut-brace and provided with a curtain-supporting section having a plate sliding along said strut-brace and arranged at its edges to embrace the same substantially as 95 set forth.

2. The bracket herein described having an inclined or strut brace plate and a top plate connected with the upper end of the strut-brace and notched at the juncture of such 100

parts, and the adjustable section having in-turned flanges overlapping and sliding along the edges of the strut-brace and operating in the notches of the top plate and compressed 5 or indented above the upper end of the strut-brace whereby to lock the sliding section in any desired adjustment substantially as set forth.

3. The bracket having a strut-brace plate 10 and an edge notch, substantially as described,

and the adjustable section having in-turned flanges overlapping and sliding along the edges of the strut-brace and indented above the notch substantially as set forth.

CHARLEY B. TITUS.
MONTFORD C. McMAINS.
